CLAIM

The ornamental design for fog resistant goggles, as shown and described.

DESCRIPTION

FIG. 1 is a front elevational view of the fog resistant goggles; FIG. 2 is a right side elevational view thereof, the left side elevational view being a mirror image of the right side elevational view shown;

FIG. 3 is a bottom and front perspective view thereof;

FIG. 4 is a top and front perspective view thereof; and,

FIG. 5 is a bottom plan view thereof.

The broken lines in the drawings depict environmental subject matter only and form no part of the claimed design.
